US00D741070S

(12) **United States Design Patent**
Martin et al.

(10) **Patent No.:** US D741,070 S
(45) **Date of Patent:** ** Oct. 20, 2015

(54) **DISPLAY**

- (71) Applicant: **Hewlett-Packard Development Company, L.P.**, Houston, TX (US)
- (72) Inventors: **Randall W. Martin**, The Woodlands, TX (US); **Matthew G. Leck**, London (GB); **Marcus A. Hoggarth**, St. Albans (GB)
- (73) Assignee: **Hewlett-Packard Development Company, L.P.**, Houston, TX (US)

(**) Term: **14 Years**

(21) Appl. No.: **29/436,056**

(22) Filed: **Oct. 31, 2012**

(51) **LOC (10) Cl.** 06-07

(52) **U.S. Cl.**

(57) **CLAIM**

We claim the ornamental design for a display, as shown and described.

DESCRIPTION

FIG. 1 is a rear perspective view of a display; FIG. 2 is an enlarged perspective view thereof taken along line 2-2 of FIG. 1;

FIG. 3 is a rear perspective view of the display of FIG. 1 in an alternate position; FIG. 4 is a side view of the display;

FIG. 5 is a sectional view of the display of FIG. 4 along line 5-5; and, FIG. 6 is a rear view of the display.

The dash-dash broken lines in the drawings are environmental lines which do not form part of the claimed design. The short dash-long dash lines are boundary lines which do not form part of the claimed design.

1 Claim, 4 Drawing Sheets
